BOOKMARK

Alex Pascoo, Bronx, N. Y.

Application August 27, 1946, Serial No. 693,226

10 Claims. (Cl. 116—119)

1

This invention relates to devices for marking positions in a book to facilitate the reader's quick return to the desired reading position in the book. More particularly the invention deals with a device of the character described which has means for clamping the same to a part of the cover or binding of the book, with means pivotally and slidably supported in connection therewith for engaging the upper surface of an exposed page of a book and to automatically drop onto successive pages in the operation of turning the same. Still more particularly, the invention deals with a book-mark device of the class described wherein the pivoted and sliding member of the device includes a supplemental pivoted part adapting the device for use in books of relatively wide range in thickness. The novel features of the invention will be best understood from the following description when taken together with the accompanying drawing in which certain embodiments of the invention are disclosed, and in which the separate parts are designated by suitable reference characters in each of the views, and in which:

Fig. 1 is a sectional view through an edge portion of a book, illustrating the arrangement of one of my improved book-mark devices thereon and indicating the method of turning pages in the use of said device.

Fig. 2 is a plan view of the structure seen in Fig. 1, with part of the construction broken away.

Fig. 3 is a face view of the device as seen in Figs. 1 and 2.

Fig. 4 is a view similar to Fig. 2 showing a modified form of device.

Fig. 5 is a face view of the device as seen in Fig. 4; and

Fig. 6 is a perspective view of part of the device shown in Figs. 4 and 5.

In illustrating one adaptation and use of my invention, I have indicated in Figs. 1 to 3 inclusive, at 10, part of a book cover, and at 11 a number of the pages of the book, 11' indicating a top page in the process of being turned beneath the marker finger or element 12 of the marker device. This finger constitutes part of a substantially U-shaped frame 13, the finger 12 comprising a short arm which parallels a longer arm 14, the latter joining the arm or finger 12 in a cross head 15, having a loop shaped finger-piece portion 16. The long arm 14 has at its free end an enlarged head 17.

The marker device also includes a mounting member 18 in the form of a strip of sheet material bent and fashioned to form a spring clip

2

19 and a wall portion 20 paralleling the wall 21 of the clip 19 and having at its free end an inwardly extending flange 22. The flange 22, as well as the folded end 23, is apertured to receive the rod 14, the portions 22 and 23 forming bearing guides in the sliding movement of the rod 14 in movement of the device into the innermost operative position shown in the drawing, and in moving the finger or arm 12 outwardly beyond the limits of the page 11.

The mounting member 18 is preferably arranged adjacent one edge portion of the book, preferably the lower edge, so that the finger or arm 12 rests, by gravity, toward the upper or rear edges of the pages 11 and in turning the pages, they are preferably slid from beneath the finger 12 in the manner indicated in 11' and as one page is removed, or turned, the finger 12 automatically drops, by gravity, onto the next adjacent page.

The finger piece 15 is used to grasp the device in returning the reader to the proper page and in assisting in opening the book at the proper page. It will be noted from a consideration of Figs. 1 and 2 of the drawing that the entire device, or for the most part, is retained within boundaries of the book covers, excepting that the fingerpiece 16 protrudes slightly for free engagement by the fingers of a hand, thus the device maintains a neat and finished appearance upon the book in connection with which it is supported.

In Figs. 4 to 6 inclusive, I have shown a slight modification in which figures, 18' represents a supporting member, identical with the member shown in Figs. 1 to 3 inclusive, and instead of using a one-piece wire frame 13, as in Figs. 1 to 3, the swinging and sliding unit of the device comprises a rod 14', generally similar to the rod 14 to the outer end of which is secured or riveted, a long lever or arm 24, preferably of strip material, as indicated.

Pivoted to the free end portion of the lever 24, as at 25, is a shorter lever 26, the free end portion of which carries a marker finger or element 12', generally similar to the finger or element 12. The free end portion of the lever 26 also has an offset flange 27 which is adapted to strike upon the upper edge of the lever 24 to limit downward movement of the lever 26, while at the same time, permitting said lever 26 to collapse so that the finger 12' may extend to the last page or pages of the book.

The outer or free end portion of the lever 24 has an offset and angularly arranged stop plate 28 which checks swinging movement of the lever

26 in the other direction. In other words, when a very thick book is being read, the two levers 24 and 26 may extend to a relatively open position, but at all times within an angle less than one hundred and eighty degrees. This enables the pin or finger 12' to be moved a much greater height than the finger 12, which swings on a definite radius with respect to the axis 14.

The device of Figs. 4 to 6 inclusive operates substantially in the same manner as shown in Figs. 1 to 3 inclusive, except that the finger 12' moves downwardly to a position closer to the rod 14', as the finger 12' reaches the bottom or lower page of the book.

It will be apparent that my improved device may be used as a marker for various types and kinds of supports other than books, wherever it is desirable to designate a position between a number of sheets or pages. In all instances, the clip or supporting member will be made to suit the particular mounting intended.

Having fully described my invention, what I claim as new and desire to secure by Letters Patent is:

1. A book-mark of the character described comprising a clip part for engagement with one cover portion of a book, a marker member, said member comprising a pair of long and short arms joined by a cross head, means slidably engaging the long arm with said clip part to extend the short arm beyond the limits of the pages of the book and within limits of the book pages when said member is in operative position, and said long arm being rotatably mounted in the clip part to provide automatic swinging movement of the short arm to engage successive pages of the book in maintaining reading positions.

2. A book-mark of the character described comprising a clip part for engagement with one cover portion of a book, a marker member, said member comprising a pair of long and short arms joined by a cross head, means slidably engaging the long arm with said clip part to extend the short arm beyond the limits of the pages of the book and within limits of the book pages when said member is in operative position, said long arm being rotatably mounted in the clip part to provide automatic swinging movement of the short arm to engage successive pages of the book in maintaining reading positions, and said member at the intersection of the short arm with said cross head having a fingerpiece portion.

3. A book-mark of the class described comprising a clip adapted for engagement with an outer wall portion of a book, said clip having spaced wall portions apertured to form bearings, an elongated rod rotatably and slidably mounted in said bearings, a marker finger spaced with respect to and substantially paralleling said rod, the rod having sliding movement in said bearing sufficient to extend said finger into and out of engagement with book pages and means joining the finger with said rod to allow the finger to automatically move onto successive pages in maintaining a constant marker for the pages of a book.

4. A book-mark of the class described comprising a clip adapted for engagement with an outer wall portion of a book, said clip having spaced wall portions apertured to form bearings, an elongated rod rotatably and slidably mounted in said bearings, a marker finger spaced with respect to and substantially paralleling said rod, the rod having sliding movement in said bearing sufficient to extend said finger into and out of en-

gagement with book pages, means joining the finger with said rod to allow the finger to automatically move onto successive pages in maintaining a constant marker for the pages of a book, and said last named means comprising a part fixed to and swinging with the rod in the rotation thereof in said bearings.

5. A book-mark of the class described comprising a clip adapted for engagement with an outer wall portion of a book, said clip having spaced wall portions apertured to form bearings, an elongated rod rotatably and slidably mounted in said bearings, a marker finger spaced with respect to and substantially paralleling said rod, the rod having sliding movement in said bearing sufficient to extend said finger into and out of engagement with book pages, means joining the finger with said rod to allow the finger to automatically move onto successive pages in maintaining a constant marker for the pages of a book, said last named means comprising a part fixed to and swinging with the rod in the rotation thereof in said bearings, and a lever pivoted to said part and to which the finger part is secured.

6. A book-mark of the class described comprising a clip adapted for engagement with an outer wall portion of a book, said clip having spaced wall portions apertured to form bearings, an elongated rod rotatably and slidably mounted in said bearings, a marker finger spaced with respect to and substantially paralleling said rod, the rod having sliding movement in said bearing sufficient to extend said finger into and out of engagement with book pages, means joining the finger with said rod to allow the finger to automatically move onto successive pages in maintaining a constant marker for the pages of a book, said last named means comprising a part fixed to and swinging with the rod in the rotation thereof in said bearings, a lever pivoted to said part and to which the finger part is secured.

7. A book-mark of the class described comprising a clip adapted for engagement with an outer wall portion of a book, said clip having spaced wall portions apertured to form bearings, an elongated rod rotatably and slidably mounted in said bearings, a marker finger spaced with respect to and substantially paralleling said rod, the rod having sliding movement in said bearing sufficient to extend said finger into and out of engagement with book pages, means joining the finger with said rod to allow the finger to automatically move onto successive pages in maintaining a constant marker for the pages of a book, said last named means comprising a part fixed to and swinging with the rod in the rotation thereof in said bearings, a lever pivoted to said part and to which the finger part is secured, and means checking swinging movement of the lever on said part in both directions.

8. A book-mark of the class described comprising a clip adapted for engagement with an outer wall portion of a book, said clip having spaced wall portions apertured to form bearings, an elongated rod rotatably and slidably mounted in said bearings, a marker finger spaced with respect to and substantially paralleling said rod, the rod having sliding movement in said bearing sufficient to extend said finger into and out of engagement with book pages, means joining the finger with said rod to allow the finger to automatically move onto successive pages in main-

taining a constant marker for the pages of a book, said last named means comprising a part fixed to and swinging with the rod in the rotation thereof in said bearings, and means movably coupled with said part for supporting said finger to move with and independent of said part.

9. A marker device of the class described comprising a substantially U-shaped clip body, means on one wall of the clip body providing spaced longitudinal bearings arranged within terminal ends of said clip body, an elongated rod slidably engaging said bearings, means checking movement of said rod in both directions in said bearings, one of said last named means comprising an arm extending at right angles to said rod, an indicator finger substantially paralleling said rod, means joining said finger with the end portion of said arm, said arm checking movement of the finger into page engaging position, and the other checking means maintaining the finger out of engagement with pages.

10. A marker device of the class described comprising a substantially U-shaped clip body, means on one wall of the clip body providing spaced longitudinal bearings arranged within terminal

ends of said clip body, an elongated rod slidably engaging said bearings, means checking movement of said rod in both directions in said bearings, one of said last named means comprising an arm extending at right angles to said rod, an indicator finger substantially paralleling said rod, means joining said finger with the end portion of said arm, said arm checking movement of the finger into page engaging position, the other checking means maintaining the finger out of engagement with pages, said last named means comprising a lever, and means on said lever and arm checking movement of the lever in two directions relatively to said arm.
